UNITED STATES PATENT OFFICE.

WILLIAM L. FIELDS AND CHARLES T. FIELDS, OF CEDAR BLUFF, VIRGINIA,
ASSIGNORS OF ONE-THIRD TO MADISON M. HANKINS, OF SAME PLACE.

DESIGN FOR A RATCHET-BAR FOR WINDOW-FASTENERS.

SPECIFICATION forming part of Design No. 31,510, dated September 12, 1899.

Application filed August 16, 1899. Serial No. 727,452. Term of patent 14 years.

To all whom it may concern:

Be it known that we, WILLIAM L. FIELDS and CHARLES T. FIELDS, citizens of the United States, residing at Cedar Bluff, in the county 5 of Tazewell and State of Virginia, have invented and produced a new and original Design for a Ratchet-Bar for Window-Fasteners, of which the following is a full, clear, and exact description, reference being had to the accompanying drawing, in which the figure is a perspective view illustrating our design.

As shown, the ratchet-bar A is formed with a series of gradually-inclined and abruptly-ending surfaces B, and a flat protuberance C 15 appears adjoining the series of inclined surfaces, while extending the full length of the bar and above the inclined surfaces is the scalloped edge D.

The main feature of our design consists in

the inclined surfaces and a flat protuberance 20 adjoining such surfaces.

A minor feature of the design consists in the scalloped edge.

Having thus described our invention, what we claim as new, and desire to secure by Letters Patent, is—

The design for a ratchet-bar for window-fasteners, substantially as herein shown and described.

In testimony whereof we have signed our 30 names to this specification in the presence of two subscribing witnesses.

WILLIAM L. FIELDS.
CHAS. T. FIELDS.
